(57) **CLAIM**

The ornamental design for a "leash pack," as shown and described.

DESCRIPTION

FIG. 1 is a front perspective view of a leash pack, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top plan view of the leash pack once it has been spread open;

FIG. 9 is a bottom plan view thereof; and,

FIG. 10 is a rear perspective view of the leash pack mounted on a retractable dog leash.

The broken line showing of a retractable dog leash is included for the purpose of illustrating environmental structure and forms no part of the claimed design.
